(57) **CLAIM**

The ornamental design for a tip for a dental scaler, as shown and described.

DESCRIPTION

FIG. 1 is an isometric view of the tip for a dental scaler showing the new design.

FIG. 2 is a rear view thereof.

FIG. 3 is a front view thereof.

FIG. 4 is a left side view thereof.

FIG. 5 is a right side view thereof.

FIG. 6 is a top view thereof; and,

FIG. 7 is a bottom view thereof.

The stippling and shading lines shown in the drawings represent the approximate three-dimensional contour of the design, and are not intended to indicate surface decoration. The portion of the tip for a dental scaler shown in broken lines forms no part of the claimed design.
